UNITED STATES PATENT OFFICE.

PERCY B. CAMP, OF CHICAGO, ILLINOIS, ASSIGNOR TO UNIVERSAL DRAFT GEAR
ATTACHMENT CO., OF CHICAGO, ILLINOIS, A CORPORATION OF ILLINOIS.

DRAFT-PLATE.

1,180,973.

specification of Letters Patent. Patented Apr. 25, 1916.

Application filed April 13, 1915. Serial No. 21,018.

To all whom it may concern:

Be it known that I, Percy B. Camp, a citizen of the United States, and resident of Chicago, county of Cook, and State of Illinois, have invented certain new and useful Improvements in Draft-Plates, of which the following is a specification and which are illustrated in the accompanying drawings, forming a part thereof.

The invention relates to draft plates for railway cars, and its object is to provide for the convenient attachment of a bottom guide and supporting plate without weakening the draft plate. This object is attained in the structure hereinafter described, and shown in the accompanying drawings, in which—

Figure 1 is a face view of the improved draft plate; Fig. 2 is a detail plan section of the sills of a car and the draft rigging applied thereto, a portion being a sectional view on the line 2—2 of Fig. 1; Figs. 3 and 4 are sectional views on the lines 3—3 and 4—4, respectively, of Fig. 1; and Fig. 5 is an end view of the draft plate.

The improved draft plate is of cast metal, and comprises the body portion 10, a central vertical abutment 11 constituting draft and buffing lugs and being formed by giving the body portion of the plate a loop form. The upper end of the abutment 11 is closed, the top flange 12 of the draft plate extending across it; and this abutment has a bottom plate 13. Horizontal partitions, as 14, 15, extend across the interior of the abutment for the purpose of increasing its strength. One of the side walls of the abutment 11 is provided with a T-shaped aperture, as shown at 16, and the bottom plate 13 is slotted from the aperture 16 parallel with the body portion 10 of the draft plate, as indicated at 17.

The draft plate is provided with end draft and buffing shoulders 18, 19, each taking the form of a vertical flange of the plate and each being reinforced by top and bottom horizontal flanges 20, 21, a vertical

end flange 22, and an intermediate horizontal loop 23 in the body portion of the draft plate. The bottom flanges 21 supporting the end draft and buffing lugs are each provided with a bolt-hole 24. The bottom guide and follower supporting plate 25 is secured to the draft plate by means of bolts setting through the slot 17 and the bolt-holes 24, the former being entered into the slot 17 through the aperture 16. The draft plates are attached to the center sills 26, 27, of a car by means of bolts.

In Fig. 2 of the drawings there is shown an ordinary draft gear yoke 28, and followers 29, 30, 31 and 32, for coöoperating with a pair of tandem springs.

The draft plate as described is simple in construction, light in weight, and possesses great strength, and provides for the convenient attachment and removal of the bottom guide and follower-supporting plate without sacrificing strength of the intermediate stop.

I claim as my invention—

1. A draft plate comprising a body portion, a central hollow stop lug having a bottom plate, one side wall of the stop being apertured and its bottom plate being slotted from the wall aperture to receive a guide-plate attaching bolt.

2. A draft plate comprising a body portion, a central hollow stop lug having a bottom plate, one side wall of the stop being apertured and its bottom plate being slotted from the wall aperture to receive a guide-plate attaching bolt, vertical flanges adjacent the ends of the body portion forming stop lugs, horizontal top and bottom flanges reinforcing such stops, the bottom flanges having holes to receive guide-plate attaching bolts.

PERCY B. CAMP.
